UNITED STATES PATENT OFFICE.

CHESTER PROUTY, OF GALETON, PENNSYLVANIA.

SUPPORTER FOR BOOTS OR SHOES.

SPECIFICATION forming part of Letters Patent No. 379,980, dated March 27, 1888.

Application filed January 20, 1888. Serial No. 261,407. (No model.)

To all whom it may concern:

Be it known that I, CHESTER PROUTY, a citizen of the United States of America, residing at Galeton, in the county of Potter and State 5 of Pennsylvania, have invented certain new and useful Improvements in Supporters for Boots or Shoes, of which the following is a specification, reference being had therein to the accompanying drawings.

10 My invention relates to supporters for boots or shoes; and its objects are, first, to obviate the tendency to run the heel off on one side; second, to support the foot in an upright position; third, to counteract the formation of 15 crooked ankles; fourth, to prolong the life of a shoe or boot so provided, and, fifth, to attain these ends with structural simplicity or economy. I attain these purposes by the device illustrated in the accompanying drawings, in which—

20 Figure 1 represents the inner side of the inner sole of a boot or shoe provided with my invention. Fig. 2 is a side elevation of my improvement. Fig. 3 indicates a plan view of 25 my device, and Fig. 4 is a vertical section thereof on the line $y-y$ of Fig. 3.

The same designations indicate corresponding parts in the several views.

To the inner sole, A, of a boot or shoe provided with an upper, B, and a counter, C, I secure, by nailing, pegging, or sewing through the means of perforations G G' G", the device D, so that the bifurcated prongs D' D' shall be under the ball of the foot, and thus by its 30 resiliency and elasticity assist the motion of walking. The shank F is pegged or sewed on both sides of the shank of the shoe or boot by means of perforations G", while the terminal uprights F' F' run on each side of the counter 35 next to the sole-leather, between the counter and the upper, and go across the heel, where they are clinched.

The device is preferably made of good steel with spring temper, the two prongs are to be thick at the crotch and taper toward the points, 45 so as to secure pliability, and the shank is to be thicker in the center than at the ends.

Inasmuch as the heel and counter are made stiffer than customarily, the tendency to run the heel down is neutralized and additional 50 strength is imparted to the foot, which greatly aids those troubled with weak or crooked ankles. The invention thus inevitably results in subjecting the boot or shoe to less strain, and hence its life is greatly prolonged. 55

Having thus fully described my improvements, what I claim, and desire to secure by Letters Patent of the United States, is—

1. As an improved article of manufacture, the bifurcated strip D, having prongs D' D' 60 and an integral shank, F, provided with perpendicular uprights F', and having a series of perforations, G G' G", constructed as herein described, and for the purpose set forth.

2. The sole A of an ordinary boot or shoe, 65 having an upper, B, and a counter, C, in combination with the bifurcated strip D, having prongs D' D' and perforations G G' G", whereby joinder is made to the inner side of the inner sole by sewing or otherwise, the shank F, integral therewith and similarly secured, having perpendicular uprights F', which, after passing between the counter and the upper, are clinched under the heel, the whole co-operating as and for the purpose herein set forth, 70 and in the manner illustrated and specified. 75

In testimony whereof I affix my signature in presence of two witnesses.

CHESTER PROUTY.
